UNITED STATES PATENT OFFICE

MARTHA JEAN HARVEY VREDENBURGH, OF BROOKLYN, NEW YORK

DESIGN FOR A RADIO PAD

Application filed May 6, 1932. Serial No. 43,726. Term of patent 3½ years.

To whom it may concern:

Be it known that I, MARTHA JEAN HARVEY VREDENBURGH, a citizen of the United States, residing at 703 Knickerbocker Avenue, Brooklyn, in the county of Kings and State of New York, have invented a certain new, original, and ornamental Design for a Radio Pad, of which the following is a full, clear, and exact description, such as will enable others skilled in the art to which it appertains to make and use the same, reference being had to the accompanying drawing, forming part thereof.

Fig. 1 is a plan view of the radio pad when opened, showing the outside configuration of the front and back covers, in accordance with the design of my invention.

Fig. 2 is a perspective view showing the inside configuration when the radio pad is partly open.

I claim:

The ornamental design for a radio pad as shown.

In testimony whereof I affix my signature.

MARTHA JEAN HARVEY VREDENBURGH.
